UNITED STATES PATENT OFFICE.

ULYSSES GRANT McQUEEN, OF NEW YORK, N. Y.

DOOR HANGER.

Application filed April 19, 1923. Serial No. 633,197.

To all whom it may concern:

Be it known that I, ULYSSES GRANT McQUEEN, a citizen of the United States, and resident of New York, in the county of 5 New York and State of New York, have invented certain new and useful Improvements in Door Hangers, of which the following is a specification.

This invention relates to lubricating 10 means for door hangers.

My invention is designed for use in connection with door hangers of the ball-bearing construction wherein steel balls of a hanger strap are arranged in the coating 15 grooves of a supporting track on which the hanger strap is free to slide horizontally.

An object of my invention is to provide a novel, simple, reliable and inexpensive 20 means for lubricating the ball-bearings of the hanger, whereby to set up maximum freedom of action of the bearings and permit the hanger strap to move rapidly with respect to said bearings.

A still further object of my invention is 25 to provide a lubricating means of this character which will automatically operate to keep the bearings supplied with just the sufficient quantity of lubricant and without 30 possibility of gumming the bearings by an over supply of lubricant.

A still further object of the invention is 35 to provide a device of this character which can be quickly applied to or removed from the track of the hanger as the occasion demands.

The various important features will be 40 particularly pointed out hereinafter in connection with a detailed description of a number of embodiments of my invention 45 which I have selected for illustration in the accompanying drawings, in which similar reference characters indicate corresponding parts in the several views.

In the drawings:

45 Figure 1 is a front elevation of a door hanger showing my invention applied thereto, parts being shown in section.

Figure 2 is a section taken on the line 2—2 of Figure 1.

50 Figure 3 is a longitudinal section through a portion of the track showing a slightly modified form of the invention.

Figure 4 is a section taken on the line 4—4 of Figure 3.

55 Figure 5 is a perspective view of the wick shown in Figures 1 and 2.

In carrying the invention into practice, I employ a hanger consisting of a fixed horizontal track 10 formed of steel and provided with an upper V-shaped groove or ball-race 11, and a lower V-shaped groove or ball-race 12. While I have herein shown and particularly described a track having upper and lower ball-races, it shall be understood that this is not to be construed as a necessary limitation. There are cases 60 wherein a single ball-race may be employed, and there are other cases wherein three or more of such races are employed. In either instance, my invention can be properly correlated with the bearings of the hanger, so that my invention will operate with maximum efficiency against the bearings. Neither do I wish to limit myself to the 70 shape or form of the bearing grooves or race-ways herein shown. I prefer the mentioned V-shaped grooves because the walls thereof are disposed at a tangent to the balls, to lessen the resistance and friction 75 between the relatively moving parts of the structure, and cause the hanger to operate with highest efficiency.

Co-acting with the track 10 is a channel bar 13 having horizontal flanges 14 and 15, correlated to the grooves 11 and 12 and respectively provided with similar grooves 16 and 17. These grooves 11, 12, 16 and 17 are associated with bearing balls 18. At the apex of each of the grooves 11 and 12 and extending in the length of the track 80 and in longitudinal relation to said grooves, are dove-tailed channels 19. In the channels are removable correspondingly formed wicks 20. These wicks are formed of felt or other suitable well known absorbent material which operates to take up a liquid lubricant by capillary attraction and convey same to the balls 18, and in turn, cause the lubricant to be distributed, through the 85 action of adhesion, to the parts of the structure with which it comes in contact. The channels 19 are connected together at suitable intervals by passages 21 and connecting these passages are suitable feed passages 22. The last named passages preferably 90 extend to the top front edge of the track, and same are disposed so that the nozzle of an oil can or the like may be readily projected thereinto when it is desired to supply 95 the respective passages and said wicks with 100 a lubricant. The passages 22 extend above the passages 21, and in consequence thereof, 105 110

they act as wells for the lubricant and permit the latter to be gradually fed to said passages 21 to be finally taken up by capillary attraction by the wicks 20.

5 The wicks 20 extend into the ball grooves or race-ways of the track for a distance to warrant free rolling contact of the bearing balls therewith, thus inducing a capillary feed of the lubricant and causing just a 10 proper amount of lubricant to be supplied to the balls and other adjuncts of the structure. In this manner, I avoid undue gumming of the balls and adjuncts of the hanger and cause the hanger to operate with maximum 15 ease and efficiency.

In the modified form of my invention shown in Figures 3 and 4 of the drawings, the track 10^a, in lieu of having the channels 19 referred to in Figures 1 and 2, I provide 20 the track with passages 23, suitably spaced apart and having a strip of wick material threaded therethrough. I thread this strip so that spaced portions thereof are respectively arranged at opposite sides of the 25 track as shown at 24 and 25. These portions 24 and 25 project into the ball-races of the track and they are adapted to come in free rolling contact with the bearing balls. The track is provided with relatively diverging 30 passages 26—26 which merge together at the upper front edge of the track. The opposite ends of these passages open into the adjacent passages 23 and against the transverse leads 27 of the wick material. The 35 terminals 28 of the wick material may be wedged into suitable recesses 29 in the track so as to secure the material in a relatively fixed position.

While I have herein fully shown and described, and have pointed out in the appended claims certain novel features of construction, arrangement, and operation which characterize my invention, it will be understood by those skilled in the art that various

omissions, substitutions, and changes in forms, proportions, sizes, and details of the device, of the materials used, and of their operation may be made without departing from my invention.

What I claim as my invention is:

1. A structure of the class described comprising a plurality of relatively sliding members, anti-friction bodies interposed between said members, and a wick of absorbent material extending lengthwise of the members and positioned with respect to said bodies so that the latter are in constant free rolling contact therewith, and means for supplying the wick with a lubricant.

2. A track having a longitudinal ball-race, 60 and a wick of absorbent material removably secured upon the track and arranged in fixed parallel relation to the ball-race so that a bearing in said ball-race will come in free rolling contact with said wick.

3. A track having a longitudinal ball-race, and a wick of absorbent material removably secured upon the track and arranged in fixed parallel relation to the ball-race so that a bearing in said ball-race will 70 come in free rolling contact with said wick, the track having a passage opening at one end onto said wick and at its opposite end onto the front upper edge of the track.

4. A door hanger including a track having a race-way, a strip of lubricating material extending into said race-way, a member mounted to slide with respect to the track, and spherical bodies mounted in said race-way and co-acting with the walls thereof to hold the weight of the sliding member against direct contact with said lubricating material and serving to permit said bodies to roll lightly over said material.

Signed at New York, in the county of New 85 York, and State of New York, December A. D. 1922.

ULYSSES GRANT McQUEEN.
